UNITED STATES PATENT OFFICE.

ALFRED TONNELE AND WILLIAM J. CURTIS, OF WILMINGTON, DELAWARE, ASSIGNORS
TO NATIONAL ADJUSTABLE BED AND SPRING COMPANY, OF WILMINGTON, DELA-
WARE.

DESIGN FOR A BEDSTEAD.

50,000.

Specification for Design.

Patented Dec. 5, 1916.

Application filed September 2, 1916. Serial No. 118,277. Term of patent 14 years.

To all whom it may concern:

Be it known that we, ALFRED TONNELE and WILLIAM J. CURTIS, citizens of the United States, residing at Wilmington, in the county of New Castle and State of Delaware, have invented a new, original, and ornamental Design for Bedsteads, of which the following is a specification, reference being had to the accompanying drawing, forming a part thereof.

The figure is a perspective view of a bedstead showing our design.

We claim:

The ornamental design for a bedstead, as shown.

ALFRED TONNELE.
WILLIAM J. CURTIS.
